TUBE ROLL MECHANISM FOR PAPER
MAKING MACHINES

William C. Nash, Neenah, Wis., assignor of one-fifth to Mary Jones, Neenah, Wis.; one-fifth to William M. Nash, Chicago, Ill.; one-fifth to Roy A. Nash, New Rochelle, N. Y.; and one-fifth to Marie Duvall Nash, Neenah, Wis.

Application November 13, 1935, Serial No. 49,469

2 Claims. (CL. 92—44)

This invention relates to improvements in paper making machines and refers specifically to an improvement in the tube rolls of a paper making machine of the Fourdrinier type.

In the making of paper on a Fourdrinier type of machine, the pulp predominantly liquid, is discharged from the head box onto a moving wire or screen. The wire or screen passes over a series of tube rolls which contact the lower face of the screen and assist in the removal of the liquid from the pulp carried upon the upper portion of the wire. The tube rolls are usually of relatively small diameter and are rotated by their contact with the moving screen.

Of course, since the tube rolls are rotated by their contact with the screen, the peripheral speed of the surfaces of said rolls will be substantially equal to the speed of travel of the screen and the angular velocity of said rolls will depend upon the speed of travel of the screen and the diameter of the rolls. When operating the paper making machine at low speeds, the screens, of course, travel at relatively low speed and hence the rolls are not rotated at an excessive angular velocity. However, as the speed of travel of the screen increases, thereby increasing the angular velocity of the rolls, difficulty is encountered due primarily to centrifugal action of the rolls upon the liquid carrier of the pulp which seeps through the screen onto the rolls, and also upon the fact that the front sides of the rolls travel upwardly toward the screen and the rear or trailing sides of the rolls travel downwardly and away from the screen.

These phenomena, although present at all screen speeds, are accentuated at high speeds and tend to disturb ideal formation of the fibres upon the screen. Further, due to the fact that this disturbance is caused by the combined effect of the liquid carrier and the speed of the rolls, it will be most pronounced at those rolls adjacent the head box, since the pulp is dehydrated at a greater rate at its initial travel upon the screen than at the intermediate or final portion of its travel.

My invention is specifically directed to the elimination of this difficulty and resides broadly in the provision of means for decreasing the rate of rotation of the tube rolls, particularly those adjacent the head box. In other words, by the use of my invention, one of the above mentioned factors which cause disturbance of the fibers upon the screen is eliminated.

To reduce the speed of said tube rolls, that

is, to render the speed of the tube rolls independent of the speed of travel of the screen, I provide an arrangement whereby the axes of the tube rolls can be moved at a desired rectilinear speed in the direction of travel of the screen. By correlating the speed of translation of the rolls with the speed of translation of the screen the rolls can be caused to rotate at a peripheral speed substantially equal to the difference of said speeds of translation. This difference in speed may be either positive or negative, that is, if the speed of translation of the screen exceeds the translation speed of the rolls, the rolls will rotate at a peripheral speed, equal to the difference, in the direction of travel of the screen, or if the translation speed of the rolls exceeds the speed of the web, the rolls will rotate in the opposite direction to the direction of travel of the screen. However, in controlling the rate of rotation of the rolls, as described, the ultimate function of said rolls, that is, to assist in the removal of the liquid carrier, is in nowise diminished.

Other objects and advantages of my invention will be apparent from the accompanying drawings and following detail description.

In the drawings, Fig. 1 is a fragmentary side elevational view, partly in section, of a portion of a paper making machine, illustrating particularly an embodiment of my invention as applied to the tube rolls.

Fig. 1a is a continuation of Fig. 1, illustrating the deflectors between some of the tube rolls.

Fig. 2 is a diagrammatic detailed view, illustrating the disruptive action of a conventional tube roll upon the paper web.

Fig. 3 is a sectional view taken on line 3—3 of Fig. 1.

Fig. 4 is an enlarged fragmentary, detailed sectional view, illustrating the use of the deflectors which comprise an embodiment of my invention.

Referring in detail to the drawings, 1 indicates one of two oppositely disposed side frames which may be positioned on opposite sides of a portion of the wet end of a paper making machine 2. A hanger 3 carrying an open bearing 4 is mounted upon an end of each of the frames 1 in which opposite ends of shaft 5 are journaled, said shaft carrying breast roll 6. A Fourdrinier wire or screen 7 passes around breast roll 6 in the conventional manner and travels in the direction indicated by the arrow.

A sprocket wheel 8 may be mounted upon each side of the machine 2 adjacent the breast roll 6.

and a sprocket chain 8 may travel around each of said sprocket wheels. In spaced relationship with each of the sprocket wheels 8 along the length of the machine 2, is a sprocket wheel 10, Fig. 1a, over which each of the chains passes. Sprocket chains 8 at the upper portion of their travel move in the same direction as screen 7, either wheels 8 or 10 constituting the driving wheels. However, the driving of the sprocket wheels is independent of the driving of screen 7 and, as will be hereinafter more fully described, the speed of the chains 8 and screen 7 is different so that there will be relative motion between the two. Each of the chains 8 carries spaced brackets 11 which may be mounted upon spaced links of the chains, the brackets upon opposite chains being in transverse alignment. A tube roll 12 may be carried between each pair of aligned brackets 11, said rolls each having oppositely projecting stub shafts 13 which may be journaled in the respective brackets 11.

A track structure 14 is mounted upon each of the frames 1 below the path of travel of screen 7, said structure being secured to said frames by means of bolts 15 or the like. The track structure 14 is oval shaped and traverses the path of travel of the chain 8. The inner face of each oval track structure is provided with a recess 16 which also defines an endless oval path similar to the loci of the chain. A ball-bearing roller 17 is carried on each stub shaft 13 and is of a diameter slightly less than the width of the recess 16. The position of chain 8 and recess 16 is so correlated that rollers 17 may ride on one shoulder of the recess 16, and, inasmuch as the rollers are smaller in diameter than the width of the recess, pure rolling motion and substantially no sliding of the rollers takes place on the recess shoulders. By this arrangement screen 7 may be supported by rolls 12 and the weight of said screen and rolls; instead of being carried by chains 8 is carried by the track structure 14.

As has been hereinbefore described, chains 8 are adapted to be driven in the same direction as screen 7 at the upper portion of travel of said chains. Therefore, rolls 12 will be moved laterally in the direction of motion of the screen. Consequently, in view of the fact that screen 7 contacts the surfaces of said rolls and thereby rotates said rolls, the peripheral speed of the rolls will be substantially equal to the difference (either plus or minus) in the speeds of translation of the screen and chains. Obviously, by controlling the speed of translation of the chains 8 the angular velocity of the tube rolls 12 can be controlled.

In making paper upon a Fourdrinier type of machine, the pulp is initially "flowed" upon the screen from the head box which discharges the pulp upon the top of the screen adjacent the breast roll. When the speed of paper making, that is, the screen speed, is increased, the head of pulp in the head box is increased to supply the rapidly moving screen with sufficient pulp. This pressure of the pulp causes a veritable cataract of liquid through the screen adjacent the head box.

In Fig. 2 a diagrammatic view of a conventional head box 18, screen 17, breast roll 19 and tube roll 12 is shown, the head box carrying a quantity of pulp 20. When the screen 17 is traveling at a rapid rate, the head of pulp 20 in head box 18 must be relatively great in order that the proper amount of pulp be deposited upon the wire. Another result of the rapidly moving screen 17 is that roll 12 and the remaining tube rolls

(not shown) are revolved at a terrific rate. As has been hereinbefore described, the pressure of the pulp 20 in the head box drives the liquid carrier and portions of the pulp through the screen in a cataract, as indicated by the arrows at 21. In addition, for a considerable period of travel of the screen the pulp upon the screen dehydrates at a rapid rate, the liquid carrier showering through the screen. A portion of this liquid is carried upon the surface of the rapidly rotating tube rolls and by centrifugal force is thrown from the roll at a rapid rate in the direction of the resultant of the radially acting centrifugal force and the tangential force, which latter is a result of centrifugal force and the phenomena of surface tension which causes the liquid to adhere sufficiently to the surface of the roll to have tangential motion imparted to it when it is thrown from the roll.

This action of the tube rolls builds up a pressure zone at 22, that is, adjacent the advancing side of the roll 12, and a reduced pressure zone 23 adjacent the receding side of the roll. The pressure in the zone 22 tends to lift the fibres from the screen surface and otherwise disturbs the original desired lay of the fibres. The reduced pressure zone 23 tends to suck the fibres down upon the screen surface which tends to impart an objectionable wire mark upon the paper. In addition, pin-holes are formed and a one-sided shade is imparted to colored paper. Consequently, the tube rolls of the conventional paper making machine constitute one of the most serious limitations to the speed of the machine.

It can readily be seen therefore, that by controlling the rate of rotation of the rolls 12 independent of the speed of the screen 7, the difficulties attendant the rapidly rotating tube rolls are overcome. In addition, the tube rolls may be rotated as slowly or as rapidly as desired merely by controlling the speed of the chains 8 with respect to the screen 7. The chains may be driven by any suitable variable speed drive (not shown). For example, with a screen speed of 1200 feet per minute, chains 8 may be driven at a speed of 1150 or 1250 feet per minute. In the former case the rolls 12 will be so rotated as to have a peripheral speed of 50 feet per minute in a clockwise or positive direction and in the latter case the rolls will have a peripheral speed of 50 feet per minute in a counterclockwise or negative direction. Of course, any desired difference of screen speed or chain speed may be adopted and the above example is not to be construed as a limitation.

In view of the fact that the difficulty, hereinbefore described, has two factors, namely, roll speed and the presence of liquid carrier on or adjacent the rolls, the disruptive effect of the rapidly rotating rolls will not be as pronounced when the rate of dehydration of the pulp upon the screen decreased below a critical point. Consequently, it may be necessary to mount only that portion of the tube rolls of the machine adjacent the breast roll upon the endless chains. For instance, it may be found sufficient to mount only those tube rolls within six or eight feet from the breast roll upon the moving chain. However, my invention broadly contemplates mounting all or a number less than all upon a moving carrier.

As the screen progresses over the table or tube rolls, the web upon the screen loses water at a diminishing rate and even though the tube rolls are rotated at a rapid rate, the mass of liquid involved does not create a disturbance of the web

comparable to that adjacent the breast rolls. However, a serious disturbance may, under some circumstances, be created beyond the zone of the traveling rolls. To diminish this disruptive effect, I contemplate mounting, in any convenient manner, baffle plates or deflectors 24 between the rolls 25 which latter may comprise the usual tube rolls with laterally immovable axes. The baffles or deflectors may be T-shaped in section with the staff of the T vertical and between adjacent rolls and the cross-portion of the T horizontal and adjacent the lower face of the screen. With this arrangement the pressure and vacuum zones will be broken up and the liquid thrown by centrifugal force will not be permitted to injure the web.

The baffles 24, of course, could be used between adjacent tube rolls of the conventional paper making machine and in themselves would reduce the injurious effect of the rotation of the rolls.

Reverting to the chain mounted rolls, it will be noticed that, inasmuch as the rolls rotate freely, there will be no undue friction between the screen undersurface and the rolls, as would be the case were the rolls stationary. This, of course, preserves the life of the delicate, relatively expensive screen.

It is to be understood that, the carrier for the rolls 12 need not necessarily be a sprocket chain, since my invention broadly contemplates lateral movement of the axes of the rolls 12 by any means whatsoever to exercise control of the rotation of the rolls.

If desired, the usual breast roll 6 of the Fourdrinier machine 1 may be eliminated and screen 6 may be carried around the tube rolls 12 upon the sprocket wheel 8, said tube rolls and sprocket wheel acting as a breast roll.

In some instances it may be desirable to drive the screen 7 at a linear speed greater than the speed of the chains 9. In other instances, for instance, to prevent the excessive passage of filler

through the screen, the chains may be driven at a linear speed in excess of the speed of the screen whereby the rolls 12 will be rotated in a counter-clockwise direction. Broadly, my invention contemplates both methods of operation.

5

I claim as my invention:

1. In combination, a paper making machine comprising a frame, an endlessly moving paper forming screen carried by said frame, a plurality of rotatable tube rolls over which said screen moves and upon which said screen is supported, a conveyor for moving said tube rolls laterally in a plane parallel to the plane of motion of said screen, said frame being provided with a channel opening towards, and on each side of said conveyor, said channels paralleling the path of travel of said screen, a bearing carried at each end of each of said tube rolls adapted to travel in said channels whereby movement of said tube rolls at right-angles to said channel is limited.

15

2. In combination, a paper making machine comprising a frame, an endlessly moving paper forming screen carried by said frame, a plurality of rotatable tube rolls over which said screen moves and upon which said screen is supported, an endlessly moving conveyor for moving said tube rolls laterally in a plane parallel to the plane of motion of said screen, said conveyor comprising a plurality of sprocket chains, spaced sprocket wheels disposed beneath said screen over which said chains travel, said frame being provided with a channel opening towards, and on each side of said conveyor where said conveyor passes around said sprocket wheels, said channels paralleling the path of travel of the conveyor over said sprocket wheels, a bearing carried at each end of each of said tube rolls adapted to travel in said channels whereby movement of said tube rolls at right-angles to said channels is limited.
